UNITED STATES PATENT OFFICE.

KENESS F. RICE, OF EUREKA SPRINGS, ARKANSAS.

HARNESS ATTACHMENT.

SPECIFICATION forming part of Letters Patent No. 341,507, dated May 11, 1886.

Application filed March 5, 1886. Serial No. 194,164. (No model.)

To all whom it may concern:

Be it known that I, KENESS F. RICE, a citizen of the United States, residing at Eureka Springs, in the county of Carroll and State of 5 Arkansas, have invented a new and useful Improvement in Harness Attachments for Taming and Controlling Horses, of which the following is a specification, reference being had to the accompanying drawings.

10 My invention relates to an improvement in harness attachments for unruly horses; and it consists in the peculiar construction and combination of devices that will be more fully set forth hereinafter, and particularly pointed out 15 in the claims.

In the drawing, the figure is a perspective view of a harness attachment embodying my improvements applied to a horse.

10 A represents a strap, which passes over the upper jaw of a horse, and is provided at its extremities with buckles for engaging with the 20 bridle-rings on each side of the mouth. A strap, B, is fastened to the strap A, and passes up along the front side of the horse's face, the 25 rear end of the strap B being attached to a headstall, C, and is provided with a ring, D.

E represents a block, which is attached to the strap A, and is provided with two sheaves or pulleys, F and F'.

30 G represents a strap, which is attached to the saddle of the harness, and is provided with a ring or loop, H, and a block, I, having a single sheave, K.

L represents a strap, or line, one end of which 35 is attached to the loop or ring H. The said strap then passes through the ring D and over one of the pulleys in the block E, from thence back and around the pulley in the block I,

from thence forward through the ring D over the remaining pulley in the block E, and from 40 thence back through the ring D, and is attached to the usual driving-rein.

Should the horse become unruly and manifest an intention of running away, he may be readily checked by drawing on the line L, 45 as will be very readily understood.

Having thus described my invention, I claim—

1. The combination, in a harness, of the bridle having the block E on the horse's face, 50 the line having one end attached to the saddle or the other portion of the harness passed over the horse's head and through the block E, and then passed back over the horse's head and attached to the reins, substantially as de- 55 scribed.

2. The combination, with a harness attachment consisting of a strap, A, attached to the bridle-rings, the face-strap B, and the headstall C, of the ring D attached to the headstall, 60 the double pulley-block attached to the strap A, the single pulley-block attached to the saddle or other portion of the harness, and the strap L, having one end secured to the harness and passed over the pulleys in the blocks and through the ring D, whereby the horse 65 may be checked by drawing upon the said strap, substantially as described.

In testimony that I claim the foregoing as my own I have hereto affixed my signature 70 in presence of two witnesses.

KENESS F. RICE.
